(57) **CLAIM**

The ornamental design for vented pants, as shown and described.

DESCRIPTION

FIG. 1 is a perspective view of vented pants according to an embodiment of the claimed design;

FIG. 2 is a front elevational view of the vented pants of FIG. 1;

FIG. 3 is a rear elevational view of the vented pants of FIG. 1; FIG. 4 is a right elevational view of the vented pants of FIG. 1;

FIG. 5 is a left elevational view of the vented pants of FIG. 1; FIG. 6 is a top elevational view of the vented pants of FIG. 1; and,

FIG. 7 is a bottom elevational view of the vented pants of FIG. 1.

The features shown in broken lines, including those representing stitching, are environment only and not part of the claimed design.
